UNITED STATES PATENT OFFICE.

MAURITZ C. INDAHL AND WILLIAM E. CHALFANT, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

TYPE-MACHINE MATRIX.

981,193.

Specification of Letters Patent. Patented Jan. 10, 1911.

Original application filed June 7, 1909, Serial No. 500,557. Divided and this application filed July 18, 1910. Serial No. 572,528.

To all whom it may concern:

Be it known that we, MAURITZ C. INDAHL and WILLIAM E. CHALFANT, citizens of the United States, residing at Philadelphia, in 5 the county of Philadelphia and State of Pennsylvania, have invented certain new and useful Improvements in Type-Machine Matrices; and we do hereby declare the following to be a full, clear, and exact description 10 of the same, reference being had to the accompanying drawings, forming a part of this specification, and to the figures and letters of reference marked thereon.

This invention relates to matrices for the 15 cellular die cases of automatic type casting and composing machines, and is specially designed for use in connection with the die case of application Serial No. 500,557, filed June 7, 1909, of which this is a division.

20 The primary object of said invention is to provide a means for equipping the single unit cellular die-case with extended-face matrices occupying a plurality of cells, without in any degree affecting the capacity of 25 said die case to accommodate single units, whereby extended face characters may be produced in conjunction with smaller point sizes within the capacity of the single unit matrices and associated mold.

30 In the accompanying drawings—Figure 1 is a bottom plan view of the cellular die-case with the improved matrices applied thereto. Fig. 2 is a sectional view of the die-case. Fig. 3 is a perspective view of improvements as embodied in a two-unit matrix, and Fig. 4 is a similar view of a four-unit matrix embodying the invention.

The same numerals designate like parts in the several views.

40 The cellular die-case, so-called, consists of a frame or plate 1 with an opening therein divided into a series of rectangular cells of uniform dimensions and symmetrically disposed on two series of intersecting parallel 45 lines. The cells are formed by a series of removable parallel bars 2, provided with lateral fingers 3. One or more of said bars is furnished with a complementary series of fingers 4 opposite fingers 3 and a plain bar 5 is interposed between the proximate ends of fingers 4 and the ends of fingers 3 pertaining to the next adjacent bar 2. In the ordinary equipment each cell receives a single

matrix 6 of parallelepiped form and grooved peripherally as at 7 to approximately one-half the thickness of the walls of the cell, to provide interlocking suspension shoulders and permit close approximation of the sides of adjacent matrices; and each matrix is furnished with a mold-engaging surface and contained matrix cavity 8 at one end, and a conical centering cavity 9 at the opposite end. The die-case is controlled by two adjusting mechanisms operating independently on intersecting lines, 65 to bring any desired cell and its contained matrix between the end of the mold and a centering plunger in fixed relation thereto, said centering plunger, when advanced, entering the centering cavity 9 to finally position and clamp the matrix upon the mold. To 70 secure flexibility in arrangement and maximum capacity with minimum weight the normal matrices are as near as may be of the same external dimensions and the cells 75 of uniform size.

It is sometimes required, as for example when setting up advertising matter, to associate letters or characters of larger size with those represented in regular die-case 80 equipment and mold, the latter variable, set-wise, but having a fixed point dimension. To enable such extended characters to be produced automatically in association with the smaller size type it is proposed, according to the present invention, to equip the die-case with one or more matrices of abnormal dimensions adequate to produce not only the impression of the desired character 85 but also a part of the head of the type, so that when said matrix is seated upon the mold its cavity will register with and extend laterally beyond the mold-cavity, resulting in the production of a type whose body is of the same normal point size as the 90 single unit matrices and shoulder high, but whose head is extended laterally beyond the body. The overhanging portion of the head is designed to overlap and be supported upon the end of an adjacent shoulder-high quad, provision for which is made in composing the matter on the machine. To 95 accomplish this very desirable improvement without diminishing or otherwise interfering with the use and capacity of the die-case for the accommodation and distribu- 100 105

tion of single unit matrices supplemental fingers 4 on one of the bars 2 and the plain bar 5 have been introduced in the construction of the die-case and, in addition, a novel 5 form of matrix has been devised the same forming the subject of this application. The new matrix 10 is designed to occupy a plurality of the die-case cells hence its transverse section is enlarged in units of the cell, 10 Fig. 3 representing a two-unit and Fig. 4 a four-unit matrix. Each matrix is furnished with extended peripheral suspension grooves 7 to receive the outer fingers and bars of the two or more cells occupied by it, 15 and, in addition thereto the matrix is slotted, as at 11, for the passage of plain bar 5, and in the case of a four-unit matrix, Fig. 4, it is also slotted at 12 for the reception of the intermediate fingers 3 or 4 or both. Each 20 matrix is thus provided with a plurality of retaining, *i. e.*, supporting and squaring sections 15, one for each cell occupied,—a feature of considerable importance for preventing displacement, more especially where 25 the centering cavity is disposed eccentrically of the axis of the matrix as will presently appear.

The centering cavity 13 is located eccentrically of the matrix in alignment with that 30 one of the occupied cells registering with the die-case adjusting mechanism, and the matrix cavity 14 is justified with relation to one of the sides nearest the centering cavity, to the end that the line side of the 35 extended type may coincide with that of the single unit matrices associated therewith.

In practice the matrices and suspension bars 2 and 4 for the equipment of any given die-case are assembled according to a prearranged plan of distribution, the multiple unit or extended face matrix or matrices occupying 40 cells on opposite sides of plain bar 5

while the one-unit matrices are distributed among the remaining cells. In a complete equipment all the cells are occupied by character, quad or space matrices, but as is obvious a less number may be employed, as indicated in Fig. 1, wherein only a few of the cells are shown thus occupied.

By locating the centering cavity 13 eccentrically of the multiple cell matrices and in register with the cellular unit of the die-case the same adjusting mechanisms can be utilized for positioning both multiple and single unit matrices opposite the mold, and 55 for centering and clamping the same thereon, without any change or readjustment either in the positioning devices or the die-case.

Having thus described our invention, 60 what we claim as new, and desire to secure by Letters Patent of the United States, is—

1. A type matrix for the cellular die-case of automatic type casting machines provided with a matrix cavity in one end and 65 an eccentrically disposed centering cavity in the opposite end.

2. A type matrix of parallelepiped form grooved peripherally, slotted transversely, and provided at one end with a matrix cavity and at the opposite end with an eccentrically disposed centering cavity. 70

3. A type matrix for cellular die-cases the body whereof is slotted transversely and grooved peripherally to form suspension 75 shoulders and a plurality of retaining sections adapted to occupy adjacent cells in the die-case and be engaged by the surrounding walls thereof.

MAURITZ C. INDAHL.
